UNITED STATES PATENT OFFICE.

BÖRRE H. BÖRRESON, OF MINNEAPOLIS, MINNESOTA.

CARD OR TAG HOLDER.

1,414,251.

Specification of Letters Patent. Patented Apr. 25, 1922.

Application filed August 4, 1919. Serial No. 315,121.

To all whom it may concern:

Be it known that I, BÖRRE H. BÖRRESON, a citizen of the United States, resident of Minneapolis, county of Hennepin, State of Minnesota, have invented certain new and useful Improvements in Card or Tag Holders, of which the following is a specification.

The object of my invention is to provide a simple, inexpensive frame or holder in which a card or tag adapted for use on an automobile or other vehicle may be mounted and protected from damage by the weather.

A further object is to provide a holder which will present a neat, ornamental appearance on the dashboard or other part of the vehicle where it may be mounted.

The invention consists generally in various constructions and combinations, all as hereinafter described and particularly pointed out in the claims.

In the accompanying drawings forming part of this specification,

Figure 1 is a plan view of a card or tag holder embodying my invention,

Figure 2 is a sectional view of the blank after the first operation of the die,

Figure 3 is a similar view following the next operation of the die.

Figure 4 is a sectional view through the completed holder, showing the edges folded inwardly for locking or protecting the transparent plate in position in the holder.

In the drawing, 2 represents a plate or sheet of suitable metal, preferably of aluminum, having a depressed portion 3 formed by the application of a die thereto to provide a recess for the reception of the card or tag placed in the holder, which is inserted through the slot 4 formed in one end wall of the recess when the die is applied to press down the material to form such recess. This slot 4 extends transversely through the end wall of the recess and through it the card or tag may be easily inserted and removed.

A rib 6^a is preferably formed between the recess 2 and the edge of the plate which will exclude the dirt and moisture from the holder.

The next step in the operation is to fold

the edges of the blank to form a vertical flange 5 between which and the recess a shelf or step 6 is provided whereon the celluloid or other transparent sheet 7 is placed. 55 This sheet covers the recess and the card or tag therein and protects it from damage by wet or from other causes, while at the same time allowing the free inspection of the card and the printed matter or writing thereon. 60

When this transparent sheet has been put in place the flange 5 is rolled over upon it to the position shown in Figure 4, where the edges of the sheet are completely concealed and held firmly in the frame so that removal 65 therefrom is impossible without breaking or otherwise damaging the celluloid of which the plate is composed.

The sectional view, Figure 4, shows the manner of locking the transparent celluloid 70 plate in the frame, a space being indicated below this plate into which the tag or card is inserted.

This frame may be made in various sizes and the corners are preferably provided with 75 perforations 8 through which screws or nails may be inserted to fasten the frame to the dash-board or other suitable support.

I claim as my invention:

1. A card or tag holder comprising a metallic plate having a depressed portion forming a recess for the reception of the card or tag, and a slot in one wall of said recess through which the card may be inserted, said plate having a flanged portion encircling 80 said recess the outer portion of said flange being turned upwardly and inwardly upon a transparent plate that is seated on the inner portion of said flanges over said recess. 85

2. A card or tag holder comprising a 90 plate having a depressed portion forming a recess for the reception of a card or tag and a slot in the wall of said recess through which the card may be inserted, said plate having a flanged portion encircling said recess, the inner portion of said flange being raised to form a rib around said recess on which a transparent plate is seated, the outer portion of said flange having a part that is turned upwardly and inwardly over said 100 transparent plate for holding it in position over the card or tag. 95

3. A card or tag holder comprising a plate having a depressed portion forming a recess for the reception of a card or tag, and an opening through which the card may be inserted, said plate having a flanged portion encircling said recess, said flange having a rib formed therein on which a transparent

plate is seated, and said flange having a part that is folded inwardly over said transparent plate for holding it in position over the 10 card or tag.

In witness whereof, I have hereunto set my hand this 31st day of July, 1919.

BÖRRE H. BÖRRESON.

Certificate of Correction.

It is hereby certified that in Letters Patent No. 1,414,251, granted April 25, 1922, upon the application of Börre H. Börreson, of Minneapolis, Minnesota, for an improvement in "Card or Tag Holders," an error appears in the printed specification requiring correction as follows: Page 2, after line 11, insert the following as claim 4:

4. A card or tag holder comprising a plate having a seat for a card or tag and an opening through which the card is inserted in its seat, said plate also having a flange and a shelf for a transparent plate arranged beyond the edges of said card, the edges of said flange being folded inwardly over the edges of said plate.;
and that the said Letters Patent should be read with this correction therein that the same may conform to the record of the case in the Patent Office.

Signed and sealed this 27th day of June, A. D., 1922.

[SEAL.]

KARL FENNING,
Acting Commissioner of Patents.
